UNITED STATES PATENT OFFICE

WILLIAM A. FEIGEL, OF CHICAGO, ILLINOIS, ASSIGNOR TO UNION SPECIAL MACHINE COMPANY, OF CHICAGO, ILLINOIS, A CORPORATION OF ILLINOIS

PRESSER-FOOT MECHANISM FOR SEWING MACHINES

Application filed September 3, 1925. Serial No. 54,205.

The invention relates to new and useful improvements in presser foot mechanisms for sewing machines, and more particularly to a presser foot mechanism adapted to be used in a machine for tipping shoes or similar operations, wherein short curved lines of stitches are formed.

An object of the invention is to provide a presser foot mechanism wherein the material may be firmly held on the work support during the withdrawing of the needles from the material, and at the same time wherein said material may be readily turned so as to direct the line of stitches in curved paths.

A further object of the invention is to provide a presser foot mechanism of the above type wherein the material is held on the work support by a roller presser foot located at one side of the needle or needles, and also by an auxiliary presser foot engaging the material in the region of the needles.

A still further object of the invention is to provide a presser foot mechanism of the above type, wherein the auxiliary presser foot is yieldingly pressed against the material by an independent spring mechanism which can be adjusted.

A still further object of the invention is to provide a presser foot mechanism of the above type with an edge guide located on the opposite side of the needle or needles from the roller presser foot, which is of particular advantage when vamping and tipping shoes.

These and other objects will in part be obvious and will in part be hereinafter more fully disclosed.

In the drawings which show by way of illustration one embodiment of the invention—

Figure 1 is a view from the rear of a portion of the end of a machine having the invention applied thereto;

Fig. 2 is a view from the front of the machine showing a portion of the end thereof and with the improved presser mechanism applied thereto;

Fig. 3 is a view partly in end elevation and partly in section of a sewing machine with the invention applied thereto, certain

of the parts of the machine being omitted for the sake of clearness;

Fig. 4 is a sectional view on the line 4—4 of Fig. 3;

Fig. 5 is a sectional view on the line 5—5 of Fig. 3;

Fig. 6 is a sectional view on the line 6—6 of Fig. 3;

Fig. 7 is a view partly in section and partly in plan, showing on a larger scale the end of the work supporting cylinder, the feed dogs, and the auxiliary presser foot, together with the edge guide carried thereby, and

Fig. 8 is a view showing more or less diagrammatically the needles, presser mechanism, work support and feed dogs with the material to be operated upon in the machine.

The invention is directed broadly to a presser foot mechanism for the vamping or tipping of shoes or similar work. When operating upon leather with two or more needles, and when doing such work that the material has to be turned so as to form curved lines of stitches, considerable difficulty has been experienced in properly holding the material when the needles are withdrawn therefrom, and at the same time, providing a presser mechanism for holding the material which enables the material to be readily guided and turned as desired. The present machine is provided with two needles with which suitable complementary stitch forming mechanism cooperates. These two needles form parallel lines of stitching, and are preferably set in a line diagonal to the line of feed, so that a threaded looper may cooperate with each needle. In order that the machine may be used for vamping or tipping shoes, it is desirable to use a cylindrical work support. The present machine is provided with a roller presser foot, which is located at one side of the needles so as to aid in the directing of the material for forming a curved line of stitches. The presser foot is not only located at one side of the needles, but the point of contact with the work is substantially in a line passing through the rear-most needle and at right angles to the line of feed.

This aids in the moving of the work in a curved path. In order to hold the ma- 100

terial down when the needles are raised from the work, an auxiliary presser foot has been provided which engages the material on opposite sides of both needles and centrally between the needles, when two needles are used. 5 This auxiliary presser foot is independently mounted and has an independent spring for yieldingly forcing it on to the material, so that the spring may be adjusted whereby the 10 pressure of the auxiliary foot on the material is light as compared with the pressure of the roller foot against the material. Means is provided for lifting both the auxiliary foot and the roller presser foot from the material to aid in the insertion and removal of the material. In the present machine, means is also provided whereby the roller presser foot may be raised independently of the auxiliary foot. Mounted on this auxiliary presser foot is an edge guide which is located 15 on the opposite side of the needles from the roller presser foot. This edge guide is for guiding the upper layer of leather when vamping or tipping shoes.

20 Referring more in detail to the drawings, the invention is shown applied to a sewing machine which includes a work supporting cylinder 1 of the usual construction. Said work supporting cylinder has a throat plate 2 provided with feed slots, through which the feed dogs operate. Overhanging said cylindrical work support is an arm 5, which is provided with suitable bearing lugs at the forward end thereof, in which reciprocates a 25 needle bar 6. The needle bar in the present machine is provided with two needles 7 and 8. These needles are set in a line along the line of feed diagonally, and independent loopers may be provided to cooperate with these 30 needles. This produces two parallel lines of 35 stitches. The work supporting cylinder 1 is closed by the usual hinge cover plate 9, and the loopers are disposed in rear of this cover plate. It is not thought necessary to show 40 them.

45 As a means for holding the material on the work support and feeding the material, there is provided a roller presser foot 10 and also an auxiliary presser foot 11. The roller presser foot 10 is mounted on a swinging arm 12 which is carried by a bracket 13, which bracket 13 is secured by suitable screws 14, 14 to the main presser bar 15. This main presser bar 15 is mounted on the lugs at the forward 50 end of the overhanging arm 5. Said main presser bar is provided with a laterally extending lug 16 on which a leaf spring 17 rests, which spring normally depresses said main presser bar and holds the roller foot 55 in firm engagement with the material. In rear of the main presser bar 15 is an auxiliary presser bar 18 likewise mounted in the lower lug at the forward end of the overhanging arm 5. Said auxiliary bar 18 also reciprocates in a lug 19 carried by the overhanging 60

70 arm 5. The upper lug at the forward end of the overhanging arm is provided with a bracket 20 which is formed with a bearing sleeve 21. The upper end of the auxiliary bar extends up into this bracket 20. Located in said sleeve 21 is a short movable rod 22 which rests on the upper end of the auxiliary bar 18. The sleeve 21 is formed with a recess therein indicated at 23, which is slightly larger in diameter than the recess for the upper end of the auxiliary presser bar. This rod 22 extends up into the sleeve 21. A spring 24 located in the recess 23 bears at its lower end against a shoulder on the rod 22 and its upper end bears against the inside face of a cap sleeve 26. The outer face of the upwardly projecting sleeve 21 is threaded. The inner face of the cap sleeve is likewise threaded and engages the thread on the sleeve 21. By adjusting the cap sleeve up and down, the tension of the spring 24 against the rod 22, and the pressure of the rod 22 against the auxiliary presser bar may be varied. A threaded locking sleeve 27 is also placed on the sleeve 21 and will serve as a suitable way of locking the cap sleeve in its adjusted positions.

75 The auxiliary presser foot 11 is fixed to the lower end of the presser bar 18. The lower end of the main presser bar 15 is reduced as indicated at 28, and this reduced end of the main bar extends into a suitable opening 29 through the shank of the auxiliary presser foot 11. This is a loose connection between the shank of the auxiliary presser foot, and the lower end of the main presser bar, and is for the purpose of preventing the auxiliary foot from swinging laterally so that it might be struck by the needles 7 and 8.

80 From the above it will be apparent that the main presser bar is yieldingly forced downwardly by the leaf spring 17, while the auxiliary presser bar is yieldingly forced downwardly by the spring 24. These two yielding devices are independent of each other. The tension of the spring on the auxiliary foot may be set so that the foot will bear lightly upon the material, as compared with the pressure of the main roller foot on the material. Rigidly secured to the main presser bar 15 is a forked arm 30 which straddles the auxiliary presser bar 18 as clearly shown in Fig. 6. The purpose of this arm is to prevent the main presser bar from oscillating in the supporting lugs therefor. The 85 main presser bar can be raised by means of the hand lever 31, which lever is pivoted at 32 to the lower lug on the forward end of the overhanging arm. Said lever has a cam-shaped portion of the usual construction 90 which is adapted to engage a projecting pin 33 threaded into the main presser bar. This main presser bar may also be raised by means of a lever 34 which is pivoted at 35 to the 95 overhanging arm of the machine. This lever 100

is adapted to be connected to the treadle in the usual manner so that by depressing the treadle, the main presser foot may be raised. This lever 34 not only lifts the main presser bar, but also the auxiliary presser bar, so that both the roller foot and the auxiliary foot may be raised simultaneously, for the insertion or removal of the material being stitched. Rigidly secured to the main presser bar 15 is a collar 36 which carries the lug 16 above referred to. The spring 17 bears on the upper face of this lug 16, and the end 37 of the lever 34 extends underneath this lug 16. When the lever is depressed it will engage the lug 16 and thus lift the main presser bar. On the auxiliary presser bar 18 there is a collar 38 which carries a laterally extending lug 39. This lug 39 is likewise directly over the end 37 of the lever so that when the lever is depressed it will engage both the lug 39 and the lug 16 and lift not only the auxiliary foot but the main foot. The width of the lug 16 vertically is greater than that of the lug 39, and therefore, the leaf spring 17, while bearing upon the lug 16, will be above the lug 39 to a certain extent. This is for the purpose of enabling the spring 24 to control the pressure of the auxiliary presser foot 11. In other words, the auxiliary presser bar has a limited vertical movement in the supporting lugs therefore, under the tension of the spring 24. A spring 40 is provided for depressing the forward end of the lever 34. The arm 12 carrying the roller presser foot 10 is pivotally connected to an angle bracket 12^a having a horizontal slot 12^b therein, and this angle bracket is secured to another angle bracket 12^c by means of a screw 12^d. The angle bracket 12^c is in turn secured to the bracket 13 by a screw 13^a which passes through a slot 13^b in the angle bracket 12^c. This is for the purpose of permitting the roller presser foot to be properly set so as to engage the material being stitched, not only throughout the entire face of the roller foot, which of course, is angular or beveled, but also for placing the roller foot so that it will be in proper position relative to the needles to enable the material to be turned to stitch in a curved path.

The shank of the auxiliary presser foot 11 is provided with a collar 41 which is clamped to the lower end of the auxiliary presser bar 18. The auxiliary presser foot has a central finger 42 (see Fig. 7) which extends between the needles, when two needles are used. The throat plate 2 is provided with needle openings 43 and 44 for the two needles 8 and 7, respectively. Alongside of the needle opening 43 is a slot 45 for the section 46 of the feed dog. In the rear of and along the opposite side of the needle opening 44 is a slot 47 for the other section of the feed dog. This opening 47 is shown in dotted lines in Fig. 7.

The main portion of the feed dog is located in the slot 45, and the roller presser foot is directly above a portion of this section 46 of the feed dog and is also directly at one side of the needle 8. Thus it is that the material may be readily turned while it is being stitched to form a curved line of stitching. The auxiliary presser foot is likewise provided with a finger 48 which lies alongside of the needle passing through the needle opening 43. The auxiliary foot is provided with another finger 49 which is on the opposite side of the needle openings 43 and 44 from the finger 48. The purpose of these fingers of the auxiliary foot is to hold the material down when the needles are raised, so as to insure the needles being withdrawn from the material without disturbing the location of the material. This auxiliary foot, as has already been stated, bears with comparatively light pressure upon the material, and is for the primary purpose of stripping the material from the needles, while the roller presser foot insures a proper feeding of the material a stitch length. Said roller presser foot will, of course, turn as the material is fed along by the feed dog.

Associated with the auxiliary presser foot is an edge guide 50. Said edge guide is pivoted at 51 to the shank of the auxiliary presser foot. The edge guide has a portion thereof extending down through a slot in the auxiliary foot, and this guide lies between the needle opening 44 and the finger 49 of the auxiliary foot. The edge guide has its lower face curved so as to insure a ready passing of one portion of the material underneath the same, while the other portion of the material passes along the side of the edge guide and will be properly located relatively to the needles, so that both needles in a machine of the present type will pass through the material, and therefore, lines of stitches formed for securing the upper layer being stitched to the lower layer. This insures the proper placing of the sections of leather being stitched together when tipping or vamping shoes. The edge guide has a laterally projecting portion 52. The auxiliary presser foot has a forwardly projecting arm 53. Between the laterally projecting portion 52 and the arm 53 is a spring 54. This spring encircles a pin 55, which extends from the arm 53 down into the shank portion of the auxiliary foot. This pin passes through an opening in the laterally projecting portion 52 of the edge guide, and therefore, the edge guide is not only yieldingly pressed downwardly by the spring, but is guided in its up and down movements. When the auxiliary presser foot is raised, the edge guide will be pressed downwardly until the lower portion 56 strikes the auxiliary presser foot. Thus it is that the edge guide is raised with the auxiliary foot, but is capable of moving to a position below

the face of the auxiliary foot, when the auxiliary foot is held raised by the material on which it rests, so that the edge guide is positioned for guiding the upper layer of the material as above stated.

While I have shown the invention applied to a sewing machine having a cylinder bed, it will be understood, of course, that it may be used in connection with flat bed machines, and with single needle machines as well as with two needle machines. Furthermore, instead of using an independent looper with each needle, the needles may be set abreast and a single looper used therewith, making a vamper stitch.

It is obvious that minor changes in the details of construction and the arrangement of the parts may be made without departing from the spirit of the invention as set forth in the appended claims.

Having thus described the invention, what I claim as new and desire to secure by Letters Patent, is—

1. In a sewing machine, the combination of a work support, a feed dog, needles, a roller presser foot at one side of said needles, spring means for yieldingly holding said roller foot against the work, a main presser bar on which said roller foot is supported, an auxiliary presser foot mechanism including an auxiliary presser bar disposed in rear of said main presser bar, and an auxiliary presser foot on the needle side of said roller presser foot, said auxiliary presser foot having a shank rigidly secured to the lower end of said auxiliary presser bar and having a free sliding connection with said main presser bar whereby said auxiliary presser foot can move vertically independently of the main presser bar and is held from lateral movement about the axis of said auxiliary bar by said main bar and independent spring means for holding the auxiliary presser foot against the work.

2. In a sewing machine, the combination of a work support, a feed dog, needles, a roller presser foot at one side of said needles, spring means for yieldingly holding said roller foot against the work, a main presser bar on which said roller foot is supported, an auxiliary presser foot mechanism including an auxiliary presser bar disposed in rear of said main presser bar, and an auxiliary presser foot on the needle side of said roller presser foot, said auxiliary presser foot having a shank rigidly secured to the lower end of said auxiliary presser bar and having a free sliding connection with said main presser bar whereby said auxiliary presser foot can move vertically independently of the main presser bar and is held from lateral movement about the axis of said auxiliary bar by said main bar, said auxiliary foot having a slot formed therethrough, and an edge guide yieldingly mounted on the auxil-

iary foot and adapted to project through said slot and independent spring means for holding the auxiliary presser foot against the work.

3. In a sewing machine, the combination of a work support, a feed dog, needles, a roller presser foot at one side of said needles, spring means for yieldingly holding said roller foot against the work, a main presser bar on which said roller foot is supported, an auxiliary presser foot mechanism including an auxiliary presser bar disposed in rear of said main presser bar, an auxiliary presser foot on the needle side of said roller presser foot, said auxiliary presser foot having a shank rigidly secured to the lower end of said auxiliary presser bar and having a free sliding connection with said main presser bar whereby said auxiliary presser foot can move vertically independently of the main presser bar and is held from lateral movement about the axis of said auxiliary bar by said main bar, a treadle controlled lever, and lugs mounted respectively on the main and auxiliary presser bars and so disposed relative to said lever that when said lever is depressed, both of the presser bars are lifted and independent spring means for holding the auxiliary presser foot against the work.

4. In a sewing machine, the combination of a work support, a feed dog, needles, a yielding roller presser foot at one side of said needles, a main presser bar on which said roller foot is supported, an auxiliary presser foot mechanism including an auxiliary presser bar disposed in rear of said main presser bar, an auxiliary presser foot on the needle side of said roller presser foot, said auxiliary presser foot having a shank rigidly secured to the lower end of said auxiliary presser bar and having a free sliding connection with said main presser bar whereby said auxiliary presser foot can move vertically independently of the main presser bar and is held from lateral movement about the axis of said auxiliary bar by said main bar, a treadle controlled lever, lugs mounted respectively on the main and auxiliary presser bars and so disposed relative to said lever that when said lever is depressed, both of the presser bars are lifted, and a hand lever for raising said main presser bar independently of said treadle controlled lever.

5. In a sewing machine, the combination of a work support, a feed dog, needles, a yielding roller presser foot at one side of said needles, a main presser bar on which said roller foot is supported, an auxiliary presser foot mechanism including an auxiliary presser bar, an auxiliary presser foot on the needle side of said roller presser foot, said auxiliary presser foot having a shank rigidly secured to the lower end of said auxiliary presser bar and having a free sliding

- connection with said main presser bar whereby said auxiliary presser foot can move vertically independently of the main presser bar and is held from lateral movement about the axis of said auxiliary bar by said main bar, a treadle controlled lever, lugs mounted respectively on the main and auxiliary presser bars and so disposed relative to said lever that when said lever is depressed, both of the presser bars are lifted, a leaf spring bearing on the lug carried by the main presser bar for holding said roller foot in contact with the material, and an independent coiled spring adapted to engage the upper end of the auxiliary bar for yieldingly holding said auxiliary foot on the material, said lug on the auxiliary bar being located below the leaf spring whereby said auxiliary bar is free from the tension of the leaf spring.
6. A presser foot mechanism for sewing machines including a main presser bar and an auxiliary presser bar, a main foot carried by said main presser bar and an auxiliary foot carried by said auxiliary presser bar and having a free connection with the lower end of said main presser bar, whereby said auxiliary foot may yield independently of the main foot but is held from lateral movement relative to the main foot by said main presser bar, a leaf spring for holding said main presser foot in contact with the material, a coiled spring for holding the auxiliary presser foot in contact with the material, said coiled spring being located at the upper end of the auxiliary presser bar and bearing against the same, and a stationary abutment for engaging the other end of the coil spring, said abutment being adjustable for varying the tension on the coil spring.
7. A presser foot mechanism for sewing machines including a main presser bar and an auxiliary presser bar, a main foot carried by said main presser bar and an auxiliary foot carried by said auxiliary presser bar and having a free connection with the lower end of said main presser bar whereby said auxiliary foot may yield independently of the main foot but is held from lateral movement relative to the main foot by said main presser bar, a leaf spring for holding said main presser foot in contact with the material, a bracket at the upper end of the auxiliary presser bar in which said auxiliary presser bar freely moves vertically, an upwardly extending sleeve carried by said bracket, a coiled spring located in said sleeve, and devices whereby said coiled spring presses downwardly on said auxiliary presser bar, a cap sleeve for housing said auxiliary spring and serving as an abutment for the upper end thereof, said cap sleeve having threaded engagement with said bracket whereby the tension of the spring may be varied.
8. A presser foot mechanism for sewing machines including a main presser bar and an auxiliary presser bar, a main foot carried by said main presser bar and an auxiliary foot carried by said auxiliary presser bar and having a free connection with the lower end of said main presser bar whereby said auxiliary foot may yield independently of the main foot but is held from lateral movement relative to the main foot by said main presser bar, a leaf spring for holding said main presser foot in contact with the material, a coiled spring for holding the auxiliary presser foot in contact with the material, said coiled spring being located at the upper end of the auxiliary presser bar and bearing against the same, and a stationary abutment for engaging the other end of the coil spring, said abutment being adjustable for varying the tension on the coil spring.
9. In a sewing machine, the combination of a work support, a feed dog, needles, a main presser bar, a spring bearing on said main presser bar, a roller presser foot carried by said main presser bar located at one side of said needles, an auxiliary presser bar disposed in rear of said main presser bar, a spring for normally depressing said auxiliary presser bar, an auxiliary presser foot carried by said auxiliary presser bar and located on the needle side of the roller presser foot, said springs for depressing the presser bars being entirely independent of each other in their action.
10. In a sewing machine, the combination of a work support, a feed dog, needles, a main presser bar, a roller presser foot mounted on said main presser bar, spring means for depressing said main presser bar, an auxiliary presser bar disposed in rear of said main presser bar, an auxiliary presser foot carried by said auxiliary presser bar and having a free sliding connection with the said main presser bar whereby said auxiliary presser foot can move vertically independently of the main presser bar and is held from lateral movement about the axis of the auxiliary bar by said main bar, and spring means for normally depressing said auxiliary presser bar.
- In testimony whereof, I affix my signature.
- WILLIAM A. FEIGEL.
